LOCKING MECHANISM FOR TYPE WHEELS
OF PRINTING MACHINESFrank Kosmer, Syracuse, N. Y., assignor to Philip
N. Braun Inc., Los Angeles, Calif., a corporation
of California

Application July 14, 1945, Serial No. 605,013

3 Claims. (Cl. 101—95)

1

This invention relates to printing machines which embody type carrying members or wheels operable to set different type at the printing line and a printing mechanism including an operating member or platen movable toward and from the printing line to print on a work-piece the characters at the printing line; and has for its object locking means for holding the type carrying members or wheels in their set position, which locking means is operable by the movement of the printing member or platen from starting position toward printing position, but which is not moved out of operative position during the retrograde movement of the platen but on the contrary is releasable at the will of the operator, so that the type wheels are held with a predetermined type in printing position for printing repeatedly on different work-pieces. More specifically, it also has for its object, motion transmitting means between the operating member or platen and the locking member which includes a lost motion device embodying a spring through which the forward motion of the operating member is transmitted to the locking element but which permits the retrograde movement of the operating member without releasing the locking element.

Other objects appear throughout the specification.

The invention consists in the novel features and in the combinations and constructions hereinabove set forth and claimed.

In describing this invention, reference is had to the accompanying drawings in which like characters designate corresponding parts in all the views.

Figure 1 is a side elevation of a machine embodying this invention, the side plate or wall of the machine being removed.

Figure 2 is a sectional view on the plane of line 2—2, Figure 1.

Figure 3 is an enlarged detail view of the locking mechanism and contiguous parts shown in Figure 1, the locking mechanism being shown, as in open or released position.

Figure 4 is a view similar to Figure 3 showing the locking mechanism as in locked position and the operating member of the printing mechanism, that is, the platen being shown as part way in its movement toward printing position.

Figure 5 is a plan view of parts seen in Figure 4.

Figures 6 and 7 are enlarged views of the locking mechanism and contiguous parts, the locking mechanism being shown as in unlocked posi-

2

tion (Figure 6) and in locked position (Figure 7).

The invention is here shown as applied to a machine for printing identifying characters on pieces of laundry or on laundry tags. Each customer of a laundry has his own identifying code character or number. The pieces of laundry of each customer bear the same identifying number or character, and therefore, when the laundry is sorted, the customer's code number is printed thereon, or if the same code number previously applied grows dim is again printed thereon. The feature of this invention is a particularly simple mechanism for locking the type wheels in set position during repeated printing of the same code or code characters.

The machine here shown includes a series of type carrying members, as wheels 1, mounted upon a shaft 2 suitably mounted in a casing 3, these wheels carrying type on their peripheries 20 and being operable about the shaft 2 to set different type at the printing line L. The type wheels are operated by means of radially extending pins or handles 4 extending through slots in the top plate 5 of the machine, this top plate, 25 it being understood, having index characters along the slots, through which the pins 4 extend, indicating the type character at the printing line, when the radial arm is opposite that character on the index plate 5.

30 6 designates the inking mechanism as a whole. As the inking mechanism forms no part of this invention, further description thereof is thought to be unnecessary.

The printing mechanism includes an operating member 7 which carries a platen 8 movable toward and from the printing line L, the member 7 being here shown as a rock arm mounted on a shaft 9 in the casing and having handles 10 at its outer end adjacent and on opposite sides 40 of the platen 8.

In operation, the operator holds the piece of laundry with both hands at the same time and takes hold of the handles 10 and draws the laundry taut across the platen 8, and then operates 45 the platen from starting position to the printing position, bringing the fabric, stretched across the platen 8, against the type at the printing line. Just prior to the bringing of the platen and the interposed laundry against the type at the printing line, the inking mechanism inks the type and moves out of the path of the platen. The printing mechanism is, in this embodiment of the invention, also operated by the operating member 7, as by means of a rock arm 11 on the member 7 and having a pin which coacts with a 55

notch in a pull link latch 12 which is part of the printing mechanism. When the operating member is about half way on its movement toward printing position, the arm 11 has been moved far enough to move the link 12 far enough to actuate the inking mechanism, when a knock-off pin 13 on the arm 11 trips the latch, permitting the inking mechanism to return to starting position and get out of the way of the platen 8 during the remainder of the operation of the rock arm 11. This inking mechanism, as before stated, forms no part of the invention.

The locking mechanism includes a spring-pressed pawl 14 having a tooth 15 coating with ratchet teeth 16 on the type wheel 1, there being one pawl 14 for each type wheel, as shown in Figures 2 and 5. The pawl teeth 15 and the rack teeth 16 are at such an angle as to ratchet in either direction during setting of the wheels by their handles 4.

The locking mechanism further includes a locking element 17 common to all the pawls 14 and normally arranged in inoperative position and movable by the movement of the operating member part way toward the printing line, as from the starting position shown in Figure 3 to the position shown in Figure 4, through motion transmitting mechanism which includes a lost motion device by which the motion is transmitted through a spring during the forward movement only of the operating member 7 and moves the locking member into locking position but permits the locking member to move relatively to the locking element 17 during the retrograde movement of the operating member 7, leaving the locking element 17 in its locked position, as seen in Figures 4 and 7. As here illustrated, the motion transmitting mechanism consists of a manually operable release rod 18 slidably mounted in the case and having a handle 19 located outside of the case, the release rod 18 being connected at its inner end to the locking element 17, which, as shown, is a rock arm on the locking element 17, the hub of which is a cam 24. The motion transmitting mechanism includes a portion of this release rod 18, a spring 20 interposed between a shoulder or collar 21 on the rod and a sliding shoulder or collar 22 connected at 23 to a lug on the operating member 7.

During forward movement of the operating member 7, as from the position shown in Figure 3 to that shown in Figure 4, the motion is transmitted to the rod 18 and hence to the locking element 17 through the spring 20. During continued movement of the operating member 7, the spring compresses. When the operating member is moved toward starting position, the shoulder 22 merely retracts from the spring 20 and does not transmit retrograde motion to the rod 18. It will be understood that the operator still has hold of the handles 10 and the piece of laundry during retrograde movement of the operating member 7. The cam 24 of the locking member 17 coacts with the latches 14. The high point of the cam 24 moves up against the latches 14 when the latch teeth are between the teeth of the rack 16, and hence holds the latches 14 in their operated positions, until the operator pulls outwardly on the handle 19 of the release rod 18. Preferably, spring means is provided for preventing shifting of the locking element 17, when either in unlocked or unlocking position, and as here shown, this means consists of an over-the-center spring 25 (Figures 6 and 7) anchored at its upper end at 26 to a fixed point in the case or frame

and at its other or lower end at 27 to the rock arm of the locking member 17, and during the movement of the rock arm 17 from unlocked to locked position or from locked to unlocked position, this spring or the lower end thereof shifts from either side of a line passing through the axis of the rock arm 17 and the anchoring point 26 to the other side thereof. Normally, the pawls 14 hold the wheels from dropping down by gravity and eliminate additional counterbalancing means. During setting of the type wheels, the pawls 14 merely ratchet.

It is thus apparent that this locking mechanism is particularly simple and compact and easily applied to the printing wheels and the printing mechanism and the locking mechanism operated to locked position only during the forward movement of the platen and is not unlocked by the retrograde movement.

What I claim is:

1. In a printing machine, the combination of movable type carrying members operable individually to set different type at the printing line, and printing mechanism including a reciprocally movable operating member; of locking mechanism operable to hold the type carrying members in their set positions, including an element common to all of the type carrying members, motion transmitting mechanism between the operating member and the locking element, a spring arranged to yieldingly transmit the motion of the operating member to the locking mechanism in one direction only when the operating member is being moved from starting position toward printing position, means operable at will to shift the locking element to unlocked position, the locking element including a rock arm and the release means including a rod connected to the rock arm eccentric to its axis, and an over-the-center spring device anchored at one end at a fixed point relative to the movement of the rock arm and having its other end connected to the rock arm and movable with the rock arm during the operation of the rock arm from either side of a straight line passing through the axis of the rock arm and the anchoring point of the spring to the other side thereof.

2. In a printing machine, the combination with an enclosing casing, movable upright type carrying wheels operable individually about a horizontal axis to set different type at the printing line, and printing mechanism including a reciprocally movable operating member having a platen movable in a generally horizontal position forwardly and rearwardly toward and from the printing line, spring urged locking pawls, one for each wheel, located in the bottom portion of the casing and coating with the rear lower peripheries of the upright wheels, a movable element operable in one direction to lock all the pawls from movement when engaged with the wheels, an axially movable release rod extending horizontally of the lower portion of the casing through the front wall of the casing and connected to said element to transmit motion thereto in one direction to move the same into pawl locking position and in the other direction to release the pawls, motion transmitting means between the operating member and said rod including spring means to yieldingly transmit motion to the rod in said one direction only when the operating member is moved from starting toward printing position.

3. In a printing machine, the combination with

movable type carrying members operable individually to set different type at the printing line, and printing mechanism including a reciprocally movable operating member; of locking mechanism operable to hold the type carrying members in their set positions including ratcheting latches individual to the type carrying members and coacting therewith, an element common to all the latches and shiftable in one direction to lock the latches from ratcheting, and in the opposite direction to free the latches, motion transmitting means between the operating member and the locking element including a spring arranged to yieldingly transmit the motion of the operating member to the locking element during the movement of the operating member to effect the printing operation when the operating member is being moved from starting position toward printing position to move said element into latch locking position, the spring constituting a yielding lost motion device between the operating member and the locking element, and release mechanism including an axially movable release rod connected to said locking element to move it in the opposite direction to 25

operate the same to free the latches, the spring being located between a shoulder of the rod and a shoulder operated by the operating member to transmit the motion of the operating member to the locking element through the spring to move said element to latch locking position when said operating member is moved toward printing position.
